WASHING MACHINE FOR CASES, CANS,
AND CRATES

Joseph J. Bocchino, Dover, N. J.

Application June 3, 1950, Serial No. 165,936

3 Claims. (Cl. 134—129)

1

This invention relates to a device for washing milk and beverage bottle cases, boxes, cans, and the like.

It is an object of the instant invention to provide a more effective device for cleaning various types of carriers than heretofore known.

A further object is to decrease costs in the distribution of dairy products, beverages, and food.

Another object is to raise the standards of sanitation in the dairy, beverage, and food industries.

Other objects of the instant invention will become apparent in the course of the following specification.

In the attainment of these objectives, the washing device is made in two embodiments. In each embodiment, the article or carrier to be cleaned is moved longitudinally by an endless belt through the open ends of a super-structure, the open bottom of which is situated above two open tanks containing different types of cleaning liquid. The liquid from each tank is pumped into a series of inter-connected pipe frames mounted in the super-structure above the tanks, the endless belt passing through all the frames to carry the articles to be cleaned between jets of the liquid forced from inwardly directed outlets in the frames. In the first embodiment, reciprocable rotary motion is applied to the frames. The second embodiment is like the first except that reciprocable linear motion is applied to the frames rather than the reciprocable rotary motion of the first embodiment.

The invention will appear more clearly when taken in conjunction with the accompanying drawings showing by way of illustration a preferred embodiment of the inventive idea.

In the drawings:

Figures 1, 2 and 3 show the first embodiment of the washing device constructed in accordance with the principles of this invention, and in which:

Figure 1 is a front elevational view of the device with part of the cover broken away to more clearly show the internal construction;

Figure 2 is the left end view of the device shown in Figure 1, and

Figure 3 is a sectional view along 3—3 of Figure 1.

Figures 4 and 5 show the second embodiment of the washing device in which:

Figure 4 is a front elevational view of the device with part of the cover broken away to more clearly show the internal construction; and

Figure 5 is a sectional view along 5—5 of Figure 4.

2

Referring now in greater detail to the first embodiment of the washing device shown in Figures 1 through 3 where like reference numerals indicate like parts, reference numeral 10 indicates the carriers to be cleaned, and 11 the washing device.

The carriers 10 to be cleaned may be any of the many known types which are reused, such as the cases for milk and beverage bottles, milk cans, and crates and boxes for a wide variety of products.

The washing device 11 is constituted of a super-structure 12 located above two liquid containing tanks 13 and 14.

15 The super-structure 12 is constituted of a main frame having the two front vertical members 15 and 16 and two similar rear vertical members (not shown) which may be welded to corresponding edges of the tanks. A top horizontal rail 17 is secured by any suitable means 10 between the tops of the vertical members 15 and 16 while a similar rail 18 is disposed between the two rear vertical members. Similar end rails 20 may also be used to support the front and rear frame work so formed. A top member 19 is removably attached by any known means over the top of the main frame. A front member 21 is similarly removably disposed between the vertical members 15 and 16 and may extend downwardly to overlap the front of the later described tanks to which it is removably attached by any suitable fasteners 22. A similar back member 23 is also removably attached over the back of the super-structure. The ends of the super-structure are covered with similar removable end members 24 through which are the aligned openings 25.

40 Passing transversely through the aligned opening 25 of the end members of the super-structure at the bottom, is an endless open mesh belt, 124 which also passes through a series of like pipe frames 24, pivotally connected at the points 25 and 26 by any known means between spaced parallel supports attached longitudinally in the super-structure. Each pipe frame has inwardly directed outlets and the series of pipe frames over the tank 14 are pivotally interconnected by a pipe line 28 while the series over the tank 13 are pivotally interconnected by the pipe line 29. Maintaining both series of pipe frames reciprocably rotatable about the pivotal points is a driving rod 30, pivotally connected to each pipe frame of each series, one free end of the rod being eccentrically and pivotally connected to the fly-wheel 32 of a prime mover 33, 50 by a link 31.

The tanks 13 and 14 with open tops are located directly under the open bottom of the super-structure. The tank 14, for example, may contain a caustic solution and the tank 13 water. A pump 34 draws the caustic solution from the tank 14 through the pipe line 35 and forces it upwardly in the pipe line 36 to the flexible tube 37 connected in the inter-connecting pipe line 28, previously mentioned.

At the opposite end of the super-structure 12, 10 the pump 28 draws water from the tank 13 through the pipe line 39 and forces it upwardly to the flexible tube 40 to supply the series of pipe frames 24 over the tank 13 with water via the inter-connecting pipe line 29.

An inwardly directed baffle 41 in a vertical plane intermediate and above the tanks and leaving a sufficient opening for the passage of carriers disposed in the superstructure prevents an excess amount of caustic solution from the tank 14 from passing over to the water tank 13, assuming that the direction of motion of the belt 124 is as shown by the arrow of Figure 1. Any suitable means may be used for fastening the baffle in the frame-work of the super-structure. Adjacent the baffle 41 is another baffle 42 of flexible material so designed that it will contact a substantial part of the carriers in a wiping operation. A third baffle 43, at the outlet or delivery end of the device, at the left as shown in Figure 1, may also be installed to remove excess rinsing water from the tank 13 before the carrier passes out of the device.

In operation:

The pumps for the caustic solution and water are set in operation along with the endless belt. From any position, such as the bottle cleaning position (not shown), the cases are placed on the belt 124 which may have the known outwardly directed and spaced protrusions to prevent the carriers from slipping. As the carriers 10 enter the open or receiving end of the device, the caustic solution from the tank 14 being ejected out of the frames 24 under pressure against all the surfaces of the carrier will remove a large part of the foreign matter and the spent liquid will drop back through the open bottom of the superstructure into the tank 14 for reuse. The wiping baffle 42 and the separating baffle 41 will tend to prevent the excess caustic solution from passing over to the water tank 13. Passing through the series of pipe frames 24 over the water tank 13 and from the inwardly directed outlets of which the water is being expelled, any remaining caustic solution and foreign matter is removed while the belt transports the carriers through the open end, at the left as shown in Figure 1, to a reloading position or the like.

In the embodiment of the washing device shown in Figures 4 and 5, reference numeral 60 indicates the superstructure, 61 and 62 the liquid containing tanks, and 63 the pipe frames.

All parts of the device are identical with the previously described parts of the first embodiment except for the mounting of the pipe frames 63 which are designed for reciprocable linear motion as follows:

Longitudinal guideways 64 and 65 are secured within the super-structure as shown in Figure 5 by any known means. Coacting with the guideways are the similar wheels 66 rotatably mounted on each side of each pipe frame substantially at the center as illustrated. Of course, the driving rod of Figure 4 is not pivotally connected to the pipe frames as in Figure 1 of the first form.

The operation with the washing device of the second embodiment is the same as that previously described for the first embodiment.

It will be understood that the invention is not limited to the exact disclosure herein described but may lend itself to a variety of expressions within the scope of the appended claims.

What is claimed is:

1. A washing device for cases and the like, comprising an elongated tank structure having an open top, a case carrying belt extending above the tank structure and movable in the longitudinal direction of the tank structure, a super-structure having members disposed on opposite sides of the tank structure, end members disposed on opposite ends of the tank structure and connected with the first-mentioned members, the second-mentioned members having alined openings formed therein for the passage of the cases, and supports carried by the first-mentioned members; a plurality of longitudinally spaced pipe-frames enclosing said belt and having outlets upon the inner sides thereof for the spraying of cases upon said belt, a pipe line interconnecting said pipe-frames, means connected with said supports for supporting said pipe-frames for movement substantially in the direction of movement of said belt and in the opposite direction, a driving rod connected with said pipe-frames, a link connected with said driving rod, a fly-wheel connected with said link, a prime mover connected with said link, and a pump connected with said pipe line and connected with said tank structure below the level of the liquid therein.

2. A washing device for cases and the like, comprising an elongated tank structure having an open top, a case carrying belt extending above the tank structure and movable in the longitudinal direction of the tank structure, a super-structure having members disposed on opposite sides of the tank structure, end members disposed on opposite ends of the tank structure and connected with the first-mentioned members, the second-mentioned members having alined openings formed therein for the passage of the cases, and supports carried by the first-mentioned members; a plurality of longitudinally spaced pipe-frames enclosing said belt and having outlets upon the inner sides thereof for the spraying of cases upon said belt, a pipe line interconnecting said pipe-frames, pivots connected with said supports for supporting said pipe-frames for swinging movement substantially in the direction of movement of said belt and in the opposite direction, a driving rod connected with said pipe-frames, a link connected with said driving rod, a fly-wheel connected with said link, a prime mover connected with said link, and a pump connected with said pipe line and connected with said tank structure below the level of the liquid therein.

3. A washing device for cases and the like, comprising an elongated tank structure having an open top, a case-carrying belt extending above the tank structure and movable in the longitudinal direction of the tank structure, a super-structure having members disposed on opposite sides of the tank structure, end members disposed on opposite ends of the tank structure and connected with the first-mentioned members, the second-mentioned members having alined openings formed therein for the passage of the cases, and supports carried by the first-mentioned members; a plurality of longitudinally spaced pipe-frames enclosing said belt and having outlets upon the inner sides thereof for the spraying

of cases upon said belt, a pipe line interconnecting said pipe-frames, guides connected with said supports for supporting said pipe frames for reciprocating movement substantially in the direction of movement of said belt and in the opposite direction, a driving rod connected with said pipe-frames, a link connected with said driving rod, a fly-wheel connected with said link, a prime mover connected with said link, and a pump connected with said pipe line and connected with said tank structure below the level of the liquid therein.
